UNITED STATES PATENT OFFICE.

ERNEST N. HUMPHREY, OF NEW BRITAIN, CONNECTICUT, ASSIGNOR TO THE TRAUT & HINE MFG. COMPANY, OF NEW BRITAIN, CONNECTICUT, A CORPORATION OF CONNECTICUT.

BUCKLE.

Application filed September 1, 1922. Serial No. 585,608.

To all whom it may concern:

Be it known that I, ERNEST N. HUMPHREY, a citizen of the United States of America, residing at New Britain, Connecticut, have invented a new and useful Buckle, of which the following is a specification.

My invention relates to improvements in buckles, and is of particular utility when employed in connection with a buckle of the sheet metal type, designed particularly for use with bathing suit belts. In such use it has been found that buckles as heretofore made become accidentally disengaged, and the chief object of this invention is to provide simple and effective means for preventing such disengagement.

In the drawings—

Figure 1 is a front elevation, practically full sized, of a belt constructed to embody my invention.

Fig. 2 is a horizontal cross section, on the plane of the line 2—2 of Fig. 3.

Fig. 3 is a rear elevation.

Fig. 4 is a perspective view of a detail.

Fig. 5 is a section of a modification on a small scale.

Fig. 6 is a perspective view of one of the details of the modified form, on the same scale as Figs. 1 to 4.

1—2 represent the two members of a buckle. In the particular form shown these members are struck up from sheet metal, and two of the edges of the same are arranged to abut when the parts are interlocked, the member 1 having a setback at one edge, as indicated at 1^a, to overlap the rear of the member 2. Through this setback there is a longitudinal slot. 3 represents a flat hook formed on the part 2 and designed to pass through the slot in the member 1, to inter-engage or hook together said parts 1 and 2.

In the absence of further means, it is obvious that the hook 3 might be accidentally disengaged from the buckle member 1. To prevent this I provide a spring barrier which, in its preferred form, is struck up from a piece of relatively thin spring metal. This barrier in the form shown in Figs. 1 to 4 has what I may term a base 4, provided with perforated ears 5—5 at opposite ends, and a spring tongue portion 6, which acts as the aforesaid barrier when the parts are assembled.

The member 2 is provided with ears 7—7 to receive the ends of a bail 8, to which one end of the belt may be attached. The base 4 of the barrier is so proportioned that the ears 5—5 will substantially register with the ears 7—7, so that the ends of the bail 8 will perform the additional function of holding means for the barrier, to secure the same firmly in place at the back of the buckle member 2. 10—10 are ears at opposite edges of the member 1, between which may be pivoted a ratchet 11, by which the adjustable end 9^a of the belt may be secured to the buckle member 1.

In the form shown in Figs. 1 to 4, the spring tongue portion 6 of the barrier is formed at the edge of the base 4 nearest the hook 3, whereas, in the modification shown in Fig. 5, the spring tongue, indicated at 6^a, is formed on the edge of the base 4^a remote from the hook 3. This furnishes a somewhat longer spring and, in some instances, is a preferred construction. Otherwise, however, said constructions are substantially alike. 5^a—5^a represent the ears on the modified form of the barrier, corresponding to the ears 5—5 on the form first described.

It will be seen that by this simple construction and arrangement buckles of conventional form may be easily equipped with spring barriers, to prevent the accidental disengagement of the hook buckle member from the slotted buckle member. To connect the two members of the buckle requires merely the usual act of slipping the hook 3 through the slot in the opposite buckle member. When the hook is pulled in place the spring tongue portion of the barrier readily yields until the slotted portion passes said spring tongue, when the latter snaps out into place underneath the hook, so as to operate as a barrier to prevent the slotted member from becoming disengaged until the spring tongue portion is pressed down by the thumb or finger.

What I claim is:

1. In a buckle of the character described, two sheet metal members, one of said members having an elongated slot forming a hook passage, a hook on the other member, a yielding barrier carried by the hook member, and means for attaching one end of a belt to the hook member, said yielding barrier carried by said hook member being held in place by said belt-attaching means, said

barrier being formed of sheet metal and having perforated ears at opposite edges through which said belt-attaching means extend, means for attaching the other end 5 of said belt to the slotted member.

2. In a buckle of the character described, two sheet metal members arranged to be interlocked edge to edge, one of said members having an elongated slot forming a 10 hook passage, a hook on the other member adapted to enter said slot, means for securing one end of a belt to one of said members,

and means for securing the other end of a belt to the other member, comprising a bail, with ears on the last-mentioned member to 15 which said bail is pivoted, a sheet metal barrier comprising a base having upturned perforated ears through which the ends of said bail pass and having a flat spring ex- 20 tended on one edge thereof co-acting with the hoop proper to prevent the accidental disengagement of the slotted buckle member from the hook member.

ERNEST N. HUMPHREY.
